CONSTRUCTION MATERIAL

Albert C. Fischer, Chicago, Ill., assignor to The
Philip Carey Manufacturing Company, a cor-
poration of Ohio

Application January 27, 1927, Serial No. 164,001

4 Claims. (Cl. 94—18)

My present invention relates in general to construction material, and has particular reference to the production of preformed sheets, strips, blocks, slabs or the like, for use as insulation, roof covering, expansion joints, flooring, mats, waterproofing, and any other uses where a preformed material of the herein described qualities is needed.

The object of my present invention is to provide a constructional material consisting of a main body portion and a reinforcing member adapted to lend reinforcement and to hold the main body portion in position, which main body portion is composed of a mixture of bitumen and rubber, in such proportions that the mixture is soft and pliable, and when compressed will plastically resume its former shape. This main body portion is hence highly compressible and is especially adapted for expansion joint purposes.

Another object of my invention resides in mixing with the bitumen and the rubber a proportion of fibers or fibrous material which lends expansibility to this main body portion and thereby renders it particularly adaptable for packing material where compressible and expansible characteristics are desired, especially as in expansion joint.

For the purpose of illustrating the salient features of the invention I will select expansion joint material as a basis for describing the material and the method of fabricating the same.

With this end in view an illustrative embodiment of my invention is shown in the accompanying drawing, and in which

Figure 1 is a detailed view in perspective of a portion of an expansion joint strip embodying one form of my invention;

Figure 2 is a view in perspective embodying another form of my invention; and

Figure 3 is a view in perspective embodying still another form of my invention.

Various forms of composition roofing, expansion joints and waterproofing materials have been suggested using saturated felt sheets as a foundation material or reinforcing material for ductile or plastic, asphaltic material or composition asphaltic material, so that the asphaltic material may be reinforced to such an extent that it will retain its premoulded or preformed form without detracting from its inherent compressible or expanding qualities, which makes it acceptable for various uses to which it is to be put. In some of these forms plastic or ductile material is reinforced by a single layer of foundation material placed on one side thereof. In other forms

foundation material is applied to opposite sides, and in other forms the ductile or plastic material is made up in alternating layers with the foundation material.

In practising my present improvement I have in mind carrying out the same theory or mode of fabrication as previously suggested designs, but I use a different type of material in place of the ductile or plastic material as heretofore used. This difference applies equally well to the foundation material. What I mean by employing a different type of material is that the previously suggested forms have never disclosed the added advantage of incorporating elastic rubber-like qualities in the plastic or ductile material, so that in the case of expansion joints, as an example, not only will the material be adapted to compensate for expansion but owing to its elastic qualities it will resiliently return to its original dimensions after being compressed by expansion of the building structure between which it is interposed. Such functioning will keep the expansion joint space filled at all times, regardless of changes in the dimension of the space between the members in which the material is interposed.

I have discovered that the addition of a rubber content to a bituminous substance, such for instance as, blown asphalt, will develop elastic, rubber-like qualities in the resultant product, and this condition prevails equally well, at least for all practical purposes, where fibrous material is used as a filler for the bituminous material.

When I refer to a rubber content I have in mind incorporating either uncoagulated latex, ordinary latex, cut back rubber, reclaimed rubber, ground unvulcanized rubber, coarse unvulcanized rubber particles, or any other unvulcanized rubber material suitable for the purpose which may be combined with the asphaltic material or the asphaltic mixture. For the sake of economy I would prefer to use reclaimed rubber to develop the rubber content, and the portion used in the mixture for the layer 5 would ordinarily range from 5 to 35 per cent by weight.

In lieu of a bituminous rubber mixture the material covered by Harold B. Pullar in his Patent No. 1,409,237, granted March 14, 1922, would well serve my purpose when premoulded into the form desired and reinforced by foundation material. Other similar vulcanized oils may be employed.

When using fibrous material as a filler the proportion would vary in accordance with the nature of the fibrous material, in using sawdust, as an example, the same being a finely divided

material, I would use from 20 to 35 per cent. For a coarser fibrous material, such as excelsior or more or less coarsely ground wood, I would use about 15 to 30 per cent. The balance of the mixture would be made up of the asphaltic material or the blown bituminous-pitch compound described in the Pullar patent.

To develop a mixture I would ordinarily proceed by liquefying the blown asphalt and introducing the same into a mechanical mixer, or else this melting step would be realized in the mixer, provided the same was equipped with a steam-jacket or some other heating means suitable for the purpose. In most cases a mechanical mixer with heating equipment would be preferable, regardless of whether the blown asphalt had been previously melted or not, since it is desirable to retain the asphalt at a melting point throughout the mixing step, as the introduction of the fibrous material will solidify to some extent. However, the idea is to melt the asphalt to a consistency that will make it more or less easy to mix the fibrous material with it, including the reclaimed rubber constituent.

After the mixing step has been completed the material would be removed from the mixer, usually as a warm, plastic, workable mass, and then introduced into either an extruding machine or else converted by sheet forming apparatus into sheets, and then cut into slabs, strips, blocks or any other form which may be required. In case of extruding the material it could be extruded into the ultimate form desired without first converting it into sheets.

The blown bituminous-pitch material described by Pullar may have the fibrous material incorporated therein by melting the material to a consistency that will leave it readily mixable with the fibrous material, and the mix thereafter formed into sheets, strips or the like, as above described.

Returning again to the expansion joint material. I will take the strips of this composition material which have been formed to size by an extruding apparatus, as an example, and apply the foundation material. In instances where the material has been preformed by sheet forming apparatus, the foundation material could be applied when the material was in sheet form, i. e. prior to the time that it was cut into strips. In any event the idea would be to take a strip of elastic, rubber-like material, such as 5 in Figure 1, and apply foundation material 6 to the side thereof. In other instances I may take the elastic material 5 and apply a foundation material 6 to the opposite sides thereof, as illustrated in Figure 2; or else, as illustrated in Figure 3, I may make a built-up structure by utilizing two or more layers of elastic, rubber-like material 5, with an intermediate, or intermediate sheets or layers of the foundation material 6, and outer layers of the foundation material surfacing the built-up structure.

As still another alternative form, but not shown, I may take two layers of elastic, rubber-like material 5 and use an intermediate layer of the foundation material 6. In other words, apply a layer 5 to opposite sides of a layer 6.

For foundation material I would for the most part take advantage of the cheapness of saturated felt sheets. However, an acceptable foundation material could be developed from practically the same material as that of the elastic layer 5 by using a different grade of asphaltic composition, particularly one that would be more

rigid and not as plastic as the layer 5. I even have in mind the use of paper sheets or fabric sheets, the primary object being to utilize a foundation material which will reinforce and add rigidity to the layer 5.

It should also be taken into consideration that the foundation sheet 6 should not be as thick as the elastic rubber-like layer 5, except perhaps in instances where a multiple layer structure is developed, as for instance in Figure 3. In this case all of the layers could be of practically the same thickness.

I do not expect to realize any particular advantage from the foundation layers, except to reinforce the elastic, rubber-like layer or layers, as the case may be, but at the same time I realize that the foundation layers, in some instance, should have some degree of compressibility in order that the material will function properly. In other words, my invention consists in developing a highly compressible, elastic, rubber-like material, which is reinforced in order that the same may be properly handled and installed, and in order that it may properly function in use.

To affect economy the foundation layer may be composed of an all asphalt body, or an asphalt body having fibrous material dispersed therethru. Where the layer 5 is a single layer the foundation material 6 should predominate in thickness. Likewise where the layer 5 is on both sides the center layer 6 should predominate in thickness.

The percentage of the material in the rubber layer would more or less affect the economic value of the finished joint. It might, therefore, be advisable to have the foundation layers in thicker proportion to the rubberized layers. Likewise these rubber asphalt combinations may have fibrous material distributed thru them. Likewise the layer 5 may be of a thick, matted, fibrous material waterproofed or otherwise, as may be desired. Likewise the foundation layer may be of a thick, heavy, bulky, fibrous material with its pores thoroughly permeated with waterproofing material.

Likewise I may wish to prepare a material with a very large preponderance of comminuted fibre in the layer 6, with an asphalt mixture or any other binder having a large preponderance of fibre, say 60 to 75 per cent.

I do not wish to be limited to the structure of the layer 5, my invention residing in the resiliency of the rubber-like layer or layers, nor do I wish to be limited to the method in which these layers are assembled, as it may be advisable to have separate machines pressing the various layers thru a rolling process, and then assembling the various layers as they come from the machine thru the natural adhesiveness on the surface of the sheets while in a warm state, which requires only pressure to unite them.

For fibrous filler in any of the layers I may use wool, asbestos, hemp, flax, hair, linters, hulls, cotton fibres, in fact any suitable vegetable, mineral or animal fibre. Infusorial or diatomaceous earth also typifies suitable mineral filling. I may use other combinations of bituminous material and polymerized or vulcanized oils as long as they lend the true elastic nature of rubber, which bituminous material of itself does not possess. When I say elastic I mean true elasticity, such as rubber has, and do not refer to ductility, where the bituminous material is readily deformed and does not come back to its original form. This elasticity may be only slight where a small rubber content is employed to an in-

creasing degree of elasticity extending to a very tough and elastic material, it being understood that the preponderance of bituminous material or binder when affected by heat would create a 5 very soft elastic mass, and the increasing amount of rubber content would stiffen that mass in its respective stages until at last it will not be affected by heat to any considerable extent.

By my invention I am able to provide a constructional material having a main body portion 10 which is sluggishly elastic, inherently compressible and will sluggishly expand to its original shape. This material is particularly adaptable for expansion joint purposes, because when two 15 adjacent slabs of cement or concrete expand toward each other the intervening expansion joint must be so constructed that it will give under the pressure, but without creating a ridge on the surface of the road and thus jar traffic. With my 20 improved body this cannot occur because the composition is inherently compressible, in spite of the fact that it is also elastic and yet it will return to its normal position when the pressure is released. This new composition is much preferred over the heretofore known compositions 25 because of its high degree of inherent compressibility and re-expansibility, which quality is lent to the composition by the rubber ingredients. Reclaimed rubber is devulcanized rubber, and in 30 the process of devulcanizing it becomes soft, pudgy and more or less sticky. I prefer to use this material where my constructional material, and particularly expansion joint, is to be manufactured, because the same condition which exists 35 in the reclaimed rubber is imparted to the asphalt. Reclaimed rubber has a greater affinity for the asphalt than the raw crude rubber, which must of course as a rule be cut back with a solvent before it can be readily incorporated. In 40 raw crude the solvent would probably be kerosene, naphtha, or some like product, which when incorporated with a high melting point bituminous material would evaporate. This would not 45 impart the pudgy, sluggish condition to the asphalt which the soft, devulcanized, reclaimed

rubber would impart. In general the main body portion 5 of my improved constructional material gives the appearance of a soft and pliable, resilient, bituminized rubber, the same being black, and capable of yielding under compression and then slowly resuming its original shape. 5

Another important feature of my present invention resides in the characteristic of the main body portion that under the action of heat, the heat intensifies the compressibility and expansibility, and other characteristics of this material. This is due to the heating of the bituminous ingredients of the mixture. This quality of the material is particularly advantageous in expansion joints, where compression has previously 10 been affected during cold temperatures, and the warmth of the sun readily brings the material 15 back to life and again fills the crevice.

I claim:

1. Construction material comprising built-up 20 preformed layers, one of said layers comprising fibrated bituminous material having a rubber ingredient therein in such proportions as to give the bituminous material a relatively soft, pliable and resilient characteristic.

2. Construction material of the class described, comprising a layer of plastic bituminous material having a rubber content sufficient to give a relatively soft, pliable and compressible characteristic to the layer, said layer carrying a more 30 rigid reinforcing means.

3. A wall board construction comprising a layer of porous fabric, and a layer of semi-rigid material affixed to each side of the fabric, the 35 said layers of semi-rigid material having a composition in which asphaltum is the main ingredient.

4. A wall board construction comprising a layer of porous fabric, a layer of semi-rigid material affixed to each side of the fabric, each of 40 said layers being comprised of a mixture in which asphaltum is an ingredient, and a covering located over the outer surface of each of the layers of semi-rigid material.

ALBERT C. FISCHER. 45
